TWO-SPEED TURNTABLE DRIVE

Benjamin R. Carson, Collingswood, N. J., assignor, by means assignments, to Radio Corporation of America, New York, N. Y., a corporation of Delaware

Application January 30, 1931, Serial No. 512,244

18 Claims. (Cl. 274—9)

This invention relates to turntable drives and more particularly, although not exclusively, to a variable speed drive for a phonograph turntable.

In reproducing sound from records of the disc type, it is necessary to rotate the record disc at a constant predetermined speed. It is customary, for example, to operate phonographs such as are used in the home, at a speed of 78 or 80 R. P. M.

More recently, however, there have been introduced record tablets which are operated at a much slower speed, as, for example, those used in connection with synchronized sound and motion picture work which are operated at a speed of about 33.3 R. P. M.

It will, therefore, be obvious that a record tablet intended for reproduction by one type of phonograph apparatus, cannot be properly reproduced by another type of phonograph apparatus

and vice versa. Accordingly, my invention resides in the provision of an improved drive mechanism whereby record tablets operable at different constant angular speeds may be reproduced at their proper speed in a convenient and effective manner.

It is, therefore, the primary object of my invention to provide a drive for phonographs whereby different angular speeds may be selectively imparted to the turntable at will.

Another object of my invention is to provide a phonograph wherein the speed of the turntable may be changed at will from one constant speed to another by the simple manipulation of a lever.

Still another object of my invention is to provide a phonograph which embodies speed change mechanism whereby the angular velocity of the turntable may be instantly changed from one speed to another at will.

Another object of my invention is to provide a phonograph which is adapted for the proper reproduction of record tablets which operate at different constant angular speeds.

Still another object of my invention is to provide a phonograph having a two-speed turntable drive whereby two different types of record discs may be reproduced at their proper reproducing speed.

Still another object of my invention is to provide a phonograph mechanism which may be operated independently of or which may be combined with a portable type of moving picture projector adapted for the synchronization of sound with motion pictures, as, for example, in the home, and wherein the angular velocity of the phonograph turntable may be instantly

changed at will for the reproduction of the usual type of record tablet or special record tablets adapted for reproduction of sound in conjunction with motion pictures.

More specifically stated, it is an object of my invention to provide a speed change mechanism for phonographs whereby, under one operating condition, as, for example, in the reproduction of standard phonograph record discs, the turntable may be driven through a direct coupling to 10 a motive means at a given speed, while under another operating condition, as, for example, in the synchronization of special sound record discs with moving picture projection apparatus, the turntable will be driven by the same motive means 15 but through an indirect coupling at another given speed, the change from one coupling to the other being instantaneously at will.

The novel features that I consider characteristic of my invention are set forth with particularity in the appended claims. The invention itself, however, both as to its organization and its method of operation, together with additional objects and advantages thereof, will best be understood from the following description of a specific embodiment, when read in connection with the accompanying drawing, in which:

Fig. 1 is a fragmentary plan view of a phonograph mechanism embodying my invention, with the turntable removed;

Fig. 2 is a fragmentary view similar to Fig. 1, showing my invention with the parts thereof shown in another position;

Fig. 3 is a side elevation of a drive mechanism constructed in accordance with my invention, as 35 applied to a turntable and motor therefor with the motor board broken away and in section;

Fig. 4 is a vertical sectional view of Fig. 3; and

Fig. 5 is a fragmentary detail view of the control lever in another position from that shown 40 in Fig. 2.

Referring to the drawing, the apparatus shown comprises a constant speed motor 10 embodying a suitable reduction gear drive (not shown) which is suspended in a well-known manner from the 45 underside of a motor board 11 having a suitable opening 12 therein, with a turntable supporting spindle 13 extending upwardly from said motor through the opening 12.

A driving gear 14 is secured to the spindle 13 by 50 means of a set screw 15, said driving gear being adapted to drive the turntable 16 which is rotatably mounted on the spindle 13, through a speed change driving unit B with which the driving gear 14 cooperates.

The speed change unit B comprises a substantially annular clutch plate 17 having a bearing hub or boss 18 concentric therewith and attached thereto in any approved manner. The bearing hub 18, together with the clutch plate 17, are provided with a central bore 19 for the reception of a rotatable sleeve 20 having a ratchet flange 21 formed at the upper end thereof, and a spur gear 22 staked or otherwise secured to the opposite or lower end of the sleeve 20. From an inspection of Fig. 4, it will be apparent that the gear 22 rotates the sleeve 20 and incidentally prevents the longitudinal movement of the said sleeve in the bore 19.

Struck out from the plane of the clutch plate 17 at a point adjacent the periphery thereof, is an ear 23 so deformed that the major portion thereof is offset from the underside of the plate 17 parallel therewith. Secured to and depending from the ear 23 in spaced relation to the axial center of the gear 22, is a stub shaft 24 adapted for rotatably receiving and retaining a bearing sleeve 25 having a pair of concentrically arranged gear 26 and 27 secured thereto so that the sleeve 25 and the gears 26 and 27 will revolve as a unit. The gear 26 is of such size that it will freely mesh with the gear 22, while the gear 27 is adapted to mesh with and be driven by the driving gear 14 carried by the spindle 13, when the speed change unit B is rotatably mounted on said spindle.

Means are provided for connecting and disconnecting the clutch plate 17 in and from driving relation with the ratchet flange 21. In the illustrated embodiment of my invention, this means is constituted by a clutch mechanism of the pawl and ratchet type and comprises a curved pawl 28 which is pivoted at 29 to the upper surface of the clutch plate 17, said pawl 28 being provided with an inwardly projecting tooth 30 which is adapted for engagement with a plurality of notches or recesses 31 formed in and about the periphery of the ratchet flange 21 which rotates with the sleeve 20 relative to the turntable spindle 13 at one speed and with the spindle at another speed, above the clutch plate 17 and in the plane of the tooth 30.

A spring 32 having one end thereof secured to an upstanding pin 33 carried by one end of the pawl 28 and its opposite end to an upstanding pin 34 carried by the clutch plate 17, tends to maintain the tooth 30 in engagement with one of the recesses 31 formed in the ratchet flange 21, when the pawl 28 is in released position.

When the pawl 28 is so engaged with the ratchet flange 21, the entire speed change unit B rotates with the spindle 13 at its own speed which in operation remains constant, since the gears 22, 26, and 27 are locked against rotation about their own axes, but are carried about the axis of the spindle 18. However, when the tooth 30 formed with the pawl 28, is out of engagement with the ratchet flange 21, the clutch plate remains stationary while the ratchet flange 21 continues to revolve but at a much slower speed than the speed of the spindle 13 since the gears 22, 26, and 27 are now free to rotate about their own axes in response to the driving gear 14 which is fixed to the spindle 13.

A lever 35 adapted for controlling the speed change unit B, is pivoted intermediate its ends by means of a pivot post 36, to a base plate 37 which is secured to the motor board 11 in a position adjacent the opening 12 in the said motor board. A spring 38 having one end thereof con-

nected to the lever 35 as at 39 and its other end anchored to an upstanding pin 40 carried by the baseplate 37, functions to hold the lever 35 in either one of its two positions as clearly shown in Fig. 1.

5

The outer free end of the lever 35 is formed to provide a finger grip 41 while the opposite or inner end of the said lever is formed to provide a hook or toe 42 for engaging an abutment 43 formed on one end of the pawl 28 by means of 10 which the tooth 30 formed on the said pawl is released into or held out of engagement with the ratchet flange 21.

From an examination of Figs. 2 and 5, it will be apparent that when the lever 35 is moved to the left as seen in Fig. 1, the hook or toe 42 formed on the inner free end of the lever 35, will partially engage the abutment 43 formed on one end of the curved pawl 28 during its rotation with the clutch plate 17, as shown in Fig. 5 and thereby withdraw the tooth 30 sufficiently out of engagement with the ratchet flange 21 to free it therefrom. At the same time, it will also be apparent that the periphery of the clutch plate 17 is formed to provide a cam surface having a shoulder or step 44. From this it follows that further inward movement of the hook or toe 42 toward the spindle 13 is not possible until the shoulder 44 has passed the pin 45 carried by the lever 35, due to the rotation of the clutch plate 17 and the influence of the spring 38 on the lever 35. When this has taken place, the toe 42 will be in full engagement with the abutment 43 as clearly shown in Fig. 1.

The function of the pin 45 when in the position shown in Fig. 1 is to prevent anti-clockwise movement of the clutch plate 17 when the toe 42 and the abutment 43 are in full engagement to hold the tooth 30 out of contact with the ratchet flange 21. The said anti-clockwise movement of the clutch plate 17 would ordinarily be brought about by the pull exerted by the spring 32 on the clutch plate 17 when the pawl 28 is being held in the position shown in Fig. 1.

The preferred means for effecting a driving connection between the turntable 16 and the ratchet flange 21, forms the subject matter of my co-pending application, Serial No. 487,115, filed October 8, 1930, for "Turntable drive" and, briefly stated, comprises a vertically disposed pin 46 carried by the ratchet flange 21 and adapted to co-operate with a yieldable pin 47 vertically disposed in the hub or boss 48 formed on the underside of the turntable 16, and a friction washer 49 which is seated in an annular recess formed in the upper surface of the ratchet flange 21 for co-operation with the bottom face of the hub 48 forming a part of the turntable 16 to frictionally drive the same, the said pins 46 and 47 being adapted under certain conditions to impart a positive drive to the said turntable.

The operation of the speed change turntable drive herein illustrated and described is as follows:

Assuming that it is desired to operate a phonograph embodying my present invention for the reproduction of record tablets which operate at a constant angular speed of 78 or 80 R. P. M., such record tablets are placed upon the turntable 16 in the usual manner and the said turntable 7 released for rotation or the rotation thereof otherwise brought about in a well-known manner.

At this point, should the control lever 35 be in the position shown in Fig. 1, it must be moved 75

to the right of Fig. 1 to release the pawl 28 as clearly shown in Fig. 2 for a turntable speed of 78 R. P. M. before the sound reproducing instrumentality is placed on a record tablet of the type as above stated.

With the control lever 35 now in a position opposite to that shown in Fig. 1, it will be readily apparent that the gears 22, 26, and 27 are now locked against rotation about their axes with the result that the entire speed change unit B will rotate with the spindle 13 at its normal speed through the agency of the driving gear 14.

Conversely, if it is desired to operate a phonograph embodying my present invention for the reproduction of record tablets which operate at a constant angular speed of 33.3 R. P. M., such record tablets are placed upon the turntable 16 in the usual manner and the said turntable released for rotation or the rotation thereof otherwise brought about in a well-known manner.

At this point, should the control lever 35 be in the position shown in Fig. 2, it must be moved to the left hand position as shown in Fig. 1 to disengage the tooth 30 carried by the pawl 28, from any one of the notches 31 formed in the ratchet flange 21 to effect a turntable speed of 33.3 R. P. M., before the sound reproducing instrumentality is placed on a record tablet of the type as above stated.

With the control lever 35 now in the position shown in Fig. 1, it will be readily apparent that the gears 22, 26, and 27 are now free to rotate about their own axes. Since the entire speed change unit B is now held stationary, the driving gear 14 will drive the gear 22 which is secured to the sleeve 18, through the gears 26 and 27 whereby the ratchet flange 21 formed with the sleeve 18, will rotate at a speed which is below that of the spindle or relatively thereto due to the ratio of the said gears.

The final drive coupling between the ratchet flange 21 and the turntable 16 forms the subject matter of my copending application as herein identified.

Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

1. In a phonograph, the combination of a motor driven spindle operable at a constant predetermined speed, speed change mechanism comprising a gear train rotatably mounted on said spindle as a unit and including a clutch, a record support rotatably mounted on said spindle and adapted to be driven by said mechanism, means carried by said spindle for driving said gear train at one speed and said speed change mechanism as a unit at another speed and means for selectively controlling said clutch, whereby either one of said speeds may be transmitted to said support through said mechanism.

2. In a phonograph, the combination of a spindle operable at a constant speed, a turntable rotatably mounted on said spindle, a speed change mechanism mounted as a unit on said spindle and including a pawl and ratchet clutch, said unit being adapted to drive said turntable at a speed below that of said spindle when said clutch is disengaged and at the speed of said spindle when said clutch is in engaged position, and

manually operable means for engaging and disengaging said clutch at will.

3. In combination, a spindle operable at a constant speed, a speed change mechanism mounted on said spindle as a unit and including a pawl and ratchet clutch, means carried by said spindle for driving the mechanism of said unit, a record support rotatably mounted on said spindle and adapted to be driven by said unit, and manually operable means for controlling said clutch whereby said record support is driven by said unit at one or the other of two different speeds.

4. In a phonograph, the combination of a motor including a spindle operable at a constant speed, a record support mounted on said spindle, a speed change gear mechanism mounted on said spindle as a unit between said motor and record support and including a clutch, drive means connecting said mechanism and spindle, means carried by said mechanism for engaging and driving said record support, and means external to said record support for controlling said clutch to effect a change in the normal speed of said record support.

5. In a phonograph, the combination of a motor including a spindle operable at a constant speed, a record support revolvably mounted on said spindle, a reduction gear mechanism revolvably mounted on said spindle as a unit between said motor and record support and including a clutch, drive means connecting said mechanism and spindle, means carried by said mechanism for engaging and driving said record support, and means external to said record support for controlling said clutch to effect a change in the normal speed of said record support.

6. In a phonograph, the combination of a motor including a spindle operable at a constant speed, a record support loosely mounted on said spindle, a speed changing unit loosely mounted on said spindle between said motor and record support and including a clutch, power transfer means carried by said spindle adapted to co-operate with said unit, means carried by said unit for engaging and driving said record support, and means external to said record support for controlling said clutch to effect a change in the normal speed of said record support.

7. In a phonograph, the combination of a motor including a spindle operable at a constant speed, a gear train revolvably mounted on said spindle as a unit and including a clutch, drive means connecting said gear train and spindle, a record support revolvably mounted on said spindle and adapted to be driven by said unit, and manually operable means adapted to control said clutch whereby said record support is driven through said gear train at a speed differing from that of said spindle.

8. In a phonograph, the combination of a motor including a spindle operable at a constant speed, a record support loosely mounted on said spindle, a reduction gear mechanism loosely mounted on said spindle as a unit between said motor and record support and including a pawl and ratchet clutch, gear means carried by said spindle adapted to mesh with said mechanism, means carried by said mechanism for engaging and driving said record support, and means external to said record support for controlling said clutch to effect a change in the speed of said record support.

9. In combination, a spindle operable at a constant speed, a speed change mechanism rotatably mounted on said spindle as a unit and including

a pawl and ratchet clutch, means carried by said spindle for driving said mechanism, a record support rotatably mounted on said spindle and adapted to be driven by said unit, means manually operable at will for controlling said clutch whereby said record support is driven by said unit at one or the other of two fixed speeds, and co-operative means carried by said last-named means and said unit for preventing movement 10 of said unit at one of said two speeds.

10. In a phonograph, the combination of a motor driven spindle operable at a constant speed, a turntable loosely mounted on said spindle, a two speed driving mechanism mounted on said 15 spindle as a unit and including a pawl and ratchet clutch, drive means coupling said mechanism to said spindle, means carried by said mechanism adapted to engage and drive said turntable, manually operable means for controlling said clutch at will to selectively couple said mechanism directly and indirectly to said spindle, and means controlled by said manually operable 20 means for preventing movement of said unit when said mechanism is coupled indirectly to said mechanism is coupled indirectly to said 25 spindle.

11. In a phonograph of the type comprising a driving motor, constructed for speed thereof within a narrow range, a turntable shaft driven from the motor, a turntable thereon adapted to 30 be driven by said shaft and at the rotary speed of the latter, a speed reducing transmission between the shaft and the turntable, and means for placing said transmission at will into or out of operative connection.

35. 12. In a phonograph of the type comprising a driving motor constructed for speed thereof within a narrow range, a turntable shaft driven from the motor, a turntable thereon, and a speed reducing transmission between the shaft and the turntable, and means for short circuiting the speed reducing transmission at will for 40 fast drive of the turntable.

45. 13. A phonograph for use alternatively for conventional phonograph records and for modern slow-speed records, said phonographs including a conventional motor and a turntable shaft, a direct connection and a connection of fixed speed reducing ratio between the shaft and the turntable and manually controlled means for 50 selectively throwing said direct or said speed reducing connection into operation respectively for fast speed of the turntable and for slow speed thereof.

55. 14. A phonograph of the type including a mo-
torboard, a driving motor thereunder, a spindle

driven therefrom and protruding thereabove, a turntable on said spindle adapted to be driven directly therefrom at the rotary speed thereof, and an alternative drive between the spindle and said turntable having a fixed speed changing ratio effective to cause driving of the turntable at a rotary speed having a definite ratio with respect to that of the spindle. 5

15. The combination with a phonograph turntable adapted to rotate records of different re- 10 producing speeds, of a motor for driving said turntable, a direct drive between said motor and turntable, a differential drive therebetween, and means for selectively driving said turntable through either one of said drives. 15

16. The combination with a phonograph turntable adapted to rotate records of different re- 20 producing speeds, of a motor for driving said turntable, a shaft driven by said motor at a pre- determined speed having a driving member on 25 the end thereof, a spindle connected with said turntable having a driven member mounted thereon, and manually operated means for locking the driven member and shaft to be directly driven by said driving member when said means is moved to one position and unlocking the same for permitting said member to be indirectly driven at a different speed when said means is moved to another position.

17. In combination, a spindle operable at a 30 constant speed, a speed change mechanism mounted on said spindle as a unit and including a clutch, means carried by said spindle for driving the mechanism of said unit, a record support rotatably mounted on said spindle and 35 adapted to be driven by said unit, and manually operable means for controlling said clutch whereby said record support is driven by said unit at one or the other of two different speeds.

18. In a phonograph, the combination of a 40 motor driven spindle operable at a constant speed, a turntable loosely mounted on said spindle, a two speed driving mechanism mounted on said 45 spindle as a unit and including a clutch, drive means coupling said mechanism to said spindle, means carried by said mechanism adapted to engage and drive said turntable, manually operable means for controlling said clutch at will to selectively couple said mechanism directly and indirectly to said spindle, and means controlled 50 by said manually operable means for preventing movement of said unit when said mechanism is coupled indirectly to said spindle.

BENJAMIN R. CARSON. 55
